COVER PLATE FOR COMBINED LIGHTING FIXTURE AND RECEPTACLE

Anthony A. McCarthy, Dayton, Ohio, assignor to The
Nu Nite Lite Co., Dayton Ohio, a corporation of Ohio

Application January 22, 1958, Serial No. 49,353

Term of patent 14 years

(Cl. D26—13)

FIG-1

FIG-2

FIG-3

Fig. 1 is a front elevational view of a cover plate for combined lighting fixture and receptacle showing my new design;

Fig. 2 is a side elevational view thereof; and

Fig. 3 is a top plan view thereof.

The broken line showing of the light and switch attachments is for illustrative purposes only.

I claim:

The ornamental design for a cover plate for combined lighting fixture and receptacle, as shown and described.
